UNITED STATES PATENT OFFICE.

SAM H. LIBBY, OF EAST ORANGE, NEW JERSEY, ASSIGNOR TO SPRAGUE ELECTRIC COMPANY,
A CORPORATION OF NEW JERSEY.

GRAB-BUCKET HOIST APPARATUS.

No. 872,523.

Specification of Letters Patent.

Patented Dec. 3, 1907.

Application filed March 7, 1906. Serial No. 304,656.

To all whom it may concern:

Be it known that I, SAM H. LIBBY, a citizen of the United States, residing at East Orange, county of Essex, State of New Jersey, have invented certain new and useful improvements in Grab-Bucket Hoist Apparatus, of which the following is a specification.

The present invention relates to grab-bucket hoists and more particularly to means for controlling the motors which operate the holding and closing ropes, and it has for its object to simplify the control apparatus and to render the operation of the hoist convenient and certain.

It has been proposed to provide hoists of this character with two motors, one for the holding rope and one for the closing or hoisting rope, together with a controller for governing the operation of the motors; the controller being so arranged that both motors are set in operation to pay out their respective ropes upon lowering the bucket and to wind up the ropes in hoisting the bucket, the closing motor being started somewhat ahead of the other motor in order to close the bucket and cause it to take up a quantity of the material to be handled. With this arrangement it is evident that skilful manipulation of the controller is necessary in order that the two ropes shall not be unwound after the bucket has been dropped upon the material, since otherwise it will be possible for the slack ropes to be entangled with each other as well as with the parts of the apparatus. Similarly, in closing the bucket care must be exercised in order that no slack may be formed in the holding rope through a lifting of the bucket before the holding motor is set in operation. Not only is fouling of the ropes apt to occur, but the motors may acquire considerable momentum before assuming their loads in case the ropes are slack and thus produce objectionable jarring and jerking in the apparatus.

The present invention contemplates a system of control for the holding and closing ropes such that the objections above noted are practically obviated, since the attention which is required on the part of the operator is reduced to a minimum, and therefore the danger of the formation of slack is reduced proportionately. To this end I arrange the control apparatus so that both motors are started simultaneously when it is desired to

close the bucket, and make the motor for the holding rope of a size sufficient only to maintain the holding rope taut or else insert sufficient resistance in its circuit during the closing operation to cut down this power at 60 that time. The holding motor is never reversed, even to allow the bucket to descend, but during the descending movement of the bucket the holding rope is paid out against the drag of a load-brake, the paying out operation of course ceasing as soon as the bucket drops upon the material to be moved. Thus the only time when slack may form in either rope is during the dropping of the bucket upon the material to be moved, and 70 then, if the closing motor is not stopped at just the right instant, some slack may be formed in the closing rope but in that rope alone. The difficulties experienced in prior arrangements due to slack in the holding 75 rope are therefore entirely eliminated and but little care need be exercised by the operator to avoid difficulties on account of the closing rope.

The present invention in its various aspects will be fully understood and its objects and advantages will more clearly appear from the following description thereof taken in connection with the accompanying drawings wherein:

Figure 1 is an end elevation of a carrier adapted to move along an elevated track and provided with my improved hoisting apparatus; Fig. 2 is a side elevation of the mechanism shown in Fig. 1; Figs. 3 and 4 are details illustrating the load-brake for the holding motor; Fig. 5 is a diagram showing the two motors together with the main controller and connections; and Figs. 6 to 9, inclusive, are diagrams indicating the conditions of the 95 motor and braking circuits during the several operations of closing, raising, dumping and lowering the bucket.

Referring to Figs. 1 to 4, A represents a grab-bucket of the usual clam-shell type suspended from a traveling carrier B by holding and closing ropes 1 and 2, respectively; these ropes being mounted upon drums 3 and 4, operated by electric motors 5 and 6. 7 is a controller for governing the operation of the 105 two motors. This controller may be located in any desired position, as, for example, upon an operator's platform 8 secured to the carriage. 9 is a traverse motor for propelling the carriage along the track 10 in order to 110

convey the bucket from one point to another. Current for the several motors is obtained from trolley wires 11 and 12 through current collecting devices 13 and 14 mounted upon the carriage. These parts, except to the extent hereinafter indicated, may all take any usual or preferred forms, the particular forms shown being simply illustrative of a general type of apparatus to which the present invention may be applied. Furthermore, it is evident that the hoisting apparatus may be otherwise supported or carried than upon a carriage moving along a track.

15 In Figs. 3 and 4, 15 represents the armature of the holding motor, and 16 the usual brake associated with the armature shaft. A second brake 17 is applied to the motor armature for maintaining the holding rope taut in lowering the bucket. This latter brake consists of a disk 18 loosely mounted upon the armature shaft and arranged between a fixed collar 19 and a sliding collar 20. The disk is yieldingly gripped between these 25 two collars by reason of the action of a spring 21 arranged between the sliding collar 20 and the shoulder 22 on the shaft. A locking device consisting of an inclined plane 23 and a ball or roller 24 arranged between the inclined plane and the periphery of the disk 18, serves to hold the disk stationary when the motor is turned in the direction to pay out the holding rope, but permits the disk to rotate freely in the opposite direction. Thus 30 it will be seen that when the motor is operated to wind up the cable, the auxiliary brake mechanism has no effect, since the disk 18 revolves freely with the motor. If, however, the motor remains deenergized and the holding rope is unwound due to the weight of the descending bucket, the motor armature is rotated in the opposite direction: disk 18 is held stationary and a braking action is 35 set up between the disk and the two collars on the armature shaft dependent in amount upon the tension of the spring 21. The parts are preferably so proportioned that the auxiliary brake acts to maintain the holding rope sufficiently taut while lowering the 40 bucket without unduly retarding the movement of the bucket itself. It is evident that as soon as the pull upon the holding rope is removed, by reason of the bucket dropping upon the material to be moved, the unwinding of the holding rope instantly ceases. While the auxiliary brake may be conveniently applied to the armature shaft of the holding motor it is of course understood that the particular location of this brake is immaterial, since it is only necessary that it be so situated as to exert a retarding influence upon the holding rope in one direction but not in the other.

45 In Fig. 5 I have illustrated the motor and controller connections. The motors 5 and 6

are illustrated as series motors and the motor 5 as being smaller than the other motor but capable of assisting it in lifting the load. In closing the bucket the power of the small motor as a holding motor is cut down through the insertion of a resistance 25 in series therewith. The motors may of course be of any type or types. For sake of simplicity, the controller 7 is indicated as having only four running positions and an "off" position. In the "off" position of the controller all the circuits are interrupted and the brakes 16 and 26 associated with the motors 5 and 6, respectively, are applied. Upon moving the controller to the first running position, 50 circuits may be traced from the current collector 14^a as follows: through contacts 27, 28, 29 and 30 of the controller, through the releasing coil of the brake 16, to the return circuit,—here indicated as a ground circuit. A second circuit passes through controller contacts 27, 28, 31 and 32, through the windings of the motor 5, through resistance 25, controller contacts 36, 37, 38 and 39, to the return circuit. A further circuit may be 55 traced through controller contacts 27, 28, 33 and 34 to the armature of the motor 6, through controller contacts 40, 41, 42 and 43, through the field winding of the motor 6, controller contacts 44, 45, 46, 47, through 60 the releasing coil of the brake 26 to the return circuit. These connections are indicated in Fig. 6 and it will be seen that both of the electromagnetic brakes are released and both motors are energized so as to tend 65 to wind up their respective ropes. This is the condition of the circuits when the bucket is being closed, the motor 6 producing the closing effort and the motor 5, whose power is reduced by means of resistance 25, exerts 70 enough influence only to maintain the holding rope taut. In the second position of the controller the circuit conditions remain unchanged except that resistance 25 is cut out of the circuit of the holding motor and the 75 right-hand terminal of this motor is connected directly to the return circuit through controller contacts 35, 35', 38 and 39. This is the position to which the controller is moved after the bucket has been closed, the 80 holding motor now assisting the other motor in raising the load. When it is desired to dump the bucket, the controller is moved to the third running position and, since there are now no movable contacts on the controller to coöperate with the fixed contacts 85 30, 32, 35 and 36, the holding motor is entirely cut out and the circuit including the releasing coil of the brake 16 is interrupted so that the holding rope is locked against 90 unwinding. The connection of the field of the closing motor to the armature is reversed in this position of the controller by contacts 49, 50, 51 and 52, so that the closing motor 95 unwinds the closing rope and permits the 100

bucket to open. The circuit connections during the dumping operation are indicated in Fig. 8. After the bucket has been brought above the material to be moved, it may again be lowered upon the material by moving the controller to the fourth running position. No further changes in the circuit connections are produced except that current is now supplied to the releasing coil of the 10 brake 16 through contacts 27, 28, 53, and 30 of the controller. The circuit connections for this position of the controller are indicated in Fig. 9. It will be seen that now the brake which locks the holding rope against 15 movement is released and the holding rope may be unwound through the action of the bucket in descending. During this operation, however, the holding rope does not unwind freely but is retarded by the load- 20 brake 17 which maintains the rope taut and causes the unwinding thereof to cease immediately upon the removal of the unwinding pull, namely, as soon as the bucket reaches the material to be moved.

25 Although I have described the present invention in detail as carried out in one embodiment, I do not desire to be limited to the particular embodiment illustrated, since in its broader aspects, namely, those relating to 30 the simultaneous energization of both motors, and maintenance of the holding rope taut at all times, the present invention may be embodied in various other forms, and in the appended claims I intend covering all such 35 forms in addition to that illustrated.

What I claim as new and desire to secure by Letters Patent of the United States, is,—

1. In a grab-bucket hoist, a bucket, a holding rope and a closing rope, motors for 40 operating said ropes, a controller for causing the motor for the closing rope to operate in either direction and for causing the motor for the holding rope to operate only to wind up that rope, and means for applying tension to the holding rope while the bucket is 45 being lowered.

2. In a grab-bucket hoist, a bucket, a holding rope and a closing rope, motors for operating said ropes, means for causing the 50 motor for the closing rope to wind up the closing rope in raising the bucket and unwind the closing rope in lowering the bucket and for causing the motor for the holding rope to operate only to wind up the rope, and 55 means for paying out the holding rope under tension in lowering the bucket.

3. In a grab-bucket hoist, a bucket, a holding rope and a closing rope connected to said bucket, motors connected to said ropes 60 for operating the same, and means for simultaneously energizing the motor connected to the closing rope to close the bucket and supplying the motor connected to the holding rope with only sufficient current to maintain 65 the holding rope taut.

4. In a grab-bucket hoist, a bucket, a holding rope and a closing rope; motors for operating said ropes, and means for simultaneously energizing the motor connected to the closing rope to close the bucket and supplying the motor for the holding rope with only sufficient current to maintain the holding rope taut and for then increasing the power of the motor for the holding rope to assist the other motor in raising the bucket. 70 75

5. In a grab-bucket hoist, a bucket, a holding rope and a closing rope, a motor for said closing rope, a motor for said holding rope, a controller for said motors, a brake for maintaining said holding rope stationary in 80 dumping the bucket, and an auxiliary brake device for applying tension to said holding rope while the bucket is being lowered.

6. In a grab-bucket hoist, a bucket, a holding rope and a closing rope, a motor for 85 operating said closing rope, a motor for said holding rope, a brake for maintaining said holding rope stationary in dumping the bucket, and a brake device for permitting said holding rope to unwind under tension in 90 lowering the bucket.

7. In a grab-bucket hoist, a bucket, a holding rope and a closing rope, motors for operating said ropes, and an automatic 95 brake device for permitting the holding rope to move freely in one direction and holding it under a tension when moving in the opposite direction.

8. In a grab-bucket hoist, a bucket, a holding rope and a closing rope, motors for 100 operating said ropes, means for energizing both motors in a direction to wind up said ropes to raise the bucket and to energize one of the motors to unwind the closing rope 105 only to lower the bucket, and means for paying out the holding rope under tension in lowering the bucket.

9. In a grab-bucket hoist, a bucket, a holding rope and a closing rope, motors for operating said ropes, a controller for said 110 motors, an electro-magnetically-controlled brake associated with said holding rope, contacts on said controller for causing the aforesaid brake to be applied and the motor for the closing rope energized in a direction 115 to unwind the closing rope in dumping the bucket, and a load-brake operating to retard the unwinding of the holding rope in lowering the bucket.

10. In a grab-bucket hoist, a bucket, a holding rope and a closing rope, motors for 120 operating said ropes, electrically controlled brakes for said motors, and a controller for causing said hoisting motor to operate in either direction, for causing said holding 125 motor to operate only in a hoisting direction, and for controlling the operation of said brakes.

11. In a grab-bucket hoist, a bucket, a holding rope and a closing rope, motors for 130

- operating said ropes, electrically controlled
brakes for said motors, a controller for caus-
ing said hoisting motor to operate in either
direction, for causing said holding motor to
5 operate only in a hoisting direction, and for
controlling the operation of said brakes, and
an auxiliary braking device for putting said
holding rope under tension during the lower-
ing of the bucket.
- 10 12. In a grab-bucket hoist, a bucket, a
holding rope and a closing rope, motors for
operating said ropes, electrically operated
brakes for said motors, a resistance for cut-
ting down the power of said holding motor,

and a controller, for controlling the opera- 15
tion of said hoisting motor in both direc-
tions, for controlling the operation of the
holding motor in one direction and throwing
in or cutting out the resistance in its circuit,
and for controlling the operation of the brak- 20
ing devices.

In witness whereof, I have hereunto set
my hand this twenty third day of February,
1906.
